US0D1043067S

(12) **United States Design Patent** (10) **Patent No.:** **US D1,043,067 S**
(45) **Date of Patent:** **** Sep. 24, 2024**

(54) **SHOE OUTSOLE BOTTOM**

(71) Applicant: **Skechers U.S.A., Inc. II**, Manhattan Beach, CA (US)

(72) Inventor: **John Maxwell Weeks**, Playa del Rey, CA (US)

(73) Assignee: **Skechers U.S.A., Inc. II**, Manhattan Beach, CA (US)

(**) Term: **15 Years**

(21) Appl. No.: **29/879,707**

(22) Filed: **Jul. 11, 2023**

(51) **LOC (14) Cl.** **02-04**
U.S. Cl.

(57) **CLAIM**

The ornamental design for a shoe outsole bottom, as shown and described.

DESCRIPTION

FIG. 1 is a front perspective view of a shoe outsole bottom in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

Broken lines shown in the drawing represent environmental structure of the shoe and portions of the shoe outsole bottom that form no part of the claimed design.

1 Claim, 8 Drawing Sheets
